(57) CLAIM

The ornamental design for a paddle head, as shown and described.

DESCRIPTION

FIG. 1 is a front side view of a paddle head showing my new design;

FIG. 2 is a rear side view thereof;

FIG. 3 is a left side view thereof;

FIG. 4 is a right side view thereof;

FIG. 5 is a top elevational view thereof;

FIG. 6 is a bottom elevational view thereof;

FIG. 7 is a perspective view thereof; and,

FIG. 8 shows one embodiment of the present invention, where the paddle head of the present invention is installed to the handle end of a paddle, and the broken line showing of a paddle is for illustrative purposes only and forms no part of the claimed design.
